MATTRESS COVER

Louis Cohen, Jr., Pittsburgh, Pa.

Application July 10, 1935, Serial No. 30,681

5 Claims. (Cl. 5—354)

This invention relates to an improved cover for a mattress and similar articles.

It is the object of the invention to provide a cover of textile material for the body of a mattress to exclude effectively dust therefrom and to maintain its cleanliness. My improved cover is characterized by a marked simplicity in construction and economy in manufacture. Only little additional material and working operations are required for my construction over those generally in common use; yet a complete seal against the access of dust to the mattress is attained. Such a seal is only approximated in the structures of the prior art unless resort is had to intricate and costly expedients.

It is a further object of the invention to provide a mattress cover composed of a main casing and a closure therefor which may be applied easily to the mattress to be covered by a person without the need of additional aid. Furthermore my construction permits the turning of the mattress without affecting the comfort of the sleeper thereon.

Other objects and purposes will appear from a more detailed description of the invention following hereinafter, in conjunction with the accompanying drawings, wherein:

Fig. 1 is a perspective view of my improved mattress cover wherein the mattress is in fully covered position.

Fig. 2 is a perspective view of the mattress with the closure for the open end of the cover in open position.

Fig. 3 is a longitudinal sectional view of the cover with the mattress therein.

Fig. 4 is a bottom view of a portion of Fig. 3.

Fig. 5 is a perspective view corresponding to Fig. 1 of a second embodiment of the invention, and

Fig. 6 is a perspective view of the second embodiment of the invention showing the closure of the cover in partially opened position.

In Fig. 1 is shown a cover which is designed to cover a mattress or boxed spring body 1 to exclude dust therefrom. This cover is composed of a casing 2 which is adapted to be slipped over the mattress and a closure therefor to close effectively the open end of the casing despite shrinkage of the cover or changes in shape of the mattress. The casing 2 is formed by the end wall 3 of substantially rectangular contour and the four lateral walls 4, 5, 6 and 7, also of substantially rectangular contour extending therefrom. The walls 4 and 5 correspond to the bottom and top of the mattress, respectively, and

the walls 6 and 7 correspond to the sides thereof. The opening 8 at the end of the casing opposite to the end wall 3 is congruous to the latter and is substantially coincident with the end of the body 1. The designation of the end walls and lateral walls as such, is employed in a relative sense only, and for the purposes of the instant invention, the end walls may be of lesser area, of the same area or of greater area than some of the lateral walls. Thus the closure described below may be applied as well upon the side of a mattress cover as upon the conventional end thereof.

My novel closure for the casing is formed by sewing an end wall 11 to the edge 12 of the bottom lateral wall 5 and lateral wings 13 and 15 to the horizontal edges 14 and 16, respectively, adjacent the edge 12. An additional wing 17 extends between wings 13 and 15 and is stitched to the end wall 11. The closure in effect pivots about the edge 12, and when it is brought from the position shown in Fig. 2 to its closed position shown in Fig. 1, the wings 13, 15 and 17 overlap the extremities of the lateral walls 4, 6 and 7 and effectively cover the exposed end of the mattress body. Buttons 18 on the casing cooperate with button-holes 18' on the closure to maintain the closure in positive engagement with the casing. Any other suitable fastening means may be employed, such as hooks and eyes, snap-fasteners, ties, etc. The design of the improved mattress cover gives rise to an effective closure of the casing even though no fastening means is provided or if such fastening means is availed of only partially.

In operation, the mattress casing may be slipped onto the mattress by a single person without the need of additional help through the opening 8, at which time the closure is folded back and offers no hindrance to the movement of the cover. When the casing covers the mattress completely, the closure is lapped over the open end of the casing quickly and easily, and may be fastened thereto to maintain a positive engagement.

In the second embodiment of the invention illustrated in Figs. 5 and 6, the closure 3a for the casing 2a is formed by the end wall 21a sewed to the vertical edge 22a of one of the sides and horizontal lateral wings 24a and 25a sewed to the horizontal edges adjacent the vertical edge 22a, one of the edges only, 23a, being shown in the drawings. The additional wing 27a is bridged between the wings 24a and 25a and is attached to the end wall 21a. In this embodiment, the closure 3a in effect pivots about the edge 22a and when it is brought from its open position to its

closed position shown in Fig. 5, the wings thereof overlap the extremities of the casing 2a to obtain an effective sealing thereof. Fastening means in the form of rubber buttons 18a on the 5 casing cooperating with holes 18a' on the closure are provided to maintain the closure in positive engagement with the casing.

If desired, a plurality of pairs of short tape 10 lengths 19 may be sewed to the upper and lower edges of the opening 8 in both forms of the invention disclosed herein. The respective pairs of tape lengths may be tied together after the casing 2 is slid over the mattress and before the closure is applied over the open end. These ties 15 assure a snug fit and a perfect covering.

The edges of the cover may be continuous, 20 stitched plain or bound with tape. Thus the walls 4, 5, 6, and 7 in the first modification described above, may be in the form of a continuous piece 25 of material seamed at only one edge, or the end wall 3 may be continuous with any one or two opposite lateral walls. Likewise the lateral wings 13 and 15 may form integral continuations of wings 11, or the end wall 11 may be a continuation 30 of either or both walls 5 and 11. The invention may be realized in many ways as long as the final configuration of the casing and closure over the mattress, as illustrated herein, is obtained.

My improved construction of a mattress cover, 35 as illustrated by two preferred embodiments thereof, may be altered in several respects without departing from the spirit of the invention. Thus, for example, the wings 13 and 15 may be cut on a bias with less or no sewing thereof at the edges 14 and 16 respectively. Other changes will suggest themselves to those skilled in the art. Therefore, I desire that the scope of my invention be construed only in the light of the appended 40 claims.

40. What I claim is:

1. A cover for a mattress and analogous articles formed by a casing of textile material comprising an end wall of substantially rectangular contour and four lateral walls of substantially rectangular contour extending therefrom for substantially the complete extent of the mattress to be covered, said four lateral walls defining an opening at the end of said casing opposite said end wall and substantially congruous thereto; and a closure for said opening attached to one of said lateral walls at the edge thereof adjacent said opening and the adjacent edges of said one lateral wall, said closure having an end wall for covering said opening extending from said first-mentioned edge, a lateral wing extending from each of the said adjacent edges and connected with said last-mentioned end wall, and an additional wing extending between said lateral wings and also connected with said end wall, said wings adapted to overlap the extremities of the remaining three lateral walls.

2. A mattress cover formed by a casing and a closure as defined in claim 1, wherein fastening means is provided on said casing and said closure for maintaining the latter in engagement with said casing in the covered condition of the mattress.

3. A cover for a mattress and analogous articles formed by a casing of textile material comprising an end wall of substantially rectangular contour and four lateral walls of substantially rectangular contour extending therefrom for substantially the complete length of the mattress to be covered, two of said lateral walls corresponding to the top and bottom of the mattress and the other two lateral walls corresponding to the

sides of the mattress, said lateral walls together defining an opening at the end of said casing opposite said end wall and of like extent as said end wall, bounded by two long horizontal edges and two short vertical edges; and a closure for 5 said opening attached to one of said horizontal edges and the juxtaposed horizontal edges of the lateral walls adjacent thereto, said closure having an end wall for covering said opening extending from said one horizontal edge, a lateral wing 10 connected to said closure end wall extending from each of said adjacent horizontal edges of a height corresponding to said vertical edges, and an additional wing extending between said lateral wings and also connected with said end wall, said wings 15 adapted to overlap the extremities of three lateral walls of the casing; and cooperating fastening means at least on said additional wing and said casing for maintaining said closure in engagement therewith. 20

4. A cover for a mattress and analogous articles formed by a casing of textile material comprising an end wall of substantially rectangular contour and four lateral walls of substantially rectangular contour extending therefrom for substantially the complete length of the mattress to be covered, two of said lateral walls corresponding to the top and bottom of the mattress and the other two lateral walls corresponding to the sides of the mattress, said lateral walls together 30 defining an opening at the end of said casing opposite said end wall and of like extent as said end wall, bounded by two long horizontal edges and two short vertical edges; and a closure for said opening attached to one of said vertical edges and the juxtaposed horizontal edges of the lateral walls adjacent thereto, said closure having an end wall for covering said opening extending from said one vertical edge, a horizontal lateral wing connected to said closure end wall and extending from each of said last-mentioned horizontal edges for a distance corresponding to said long horizontal edges, and an additional wing 35 extending between said horizontal wings and also connected with said end wall, said wings adapted to overlap the extremities of the top, bottom and one of the sides of the mattress casing; and cooperating fastening means at least on said horizontal lateral wings and said casing for maintaining said closure in engagement therewith. 40

5. A cover for a mattress or analogous articles formed by a casing of flexible material having an end wall of substantially rectangular outline and four lateral walls of substantially rectangular outline extending therefrom, one of said lateral walls extending for substantially the complete extent of the mattress adapted to be covered and the remaining lateral walls extending for substantially the same extent, said four lateral walls defining an opening at the end of said casing 55 opposite said end wall and corresponding thereto; and a closure for said opening engageable with one of said lateral walls at the edge thereof adjacent said opening and the adjacent edges of said one lateral wall in both the open and closed positions of said closure relative to said casing, said closure having an end wall for covering said opening extending from said first-mentioned edge, a lateral wing extending transversely from each extremity of said end wall, and an additional wing extending between said lateral wings and also connected with said end wall, said wings adapted to overlap the extremities of the remaining three lateral walls. 60
